ATTORNEY:

UNITED STATES PATENT OFFICE.

JOSEPH F. HAYES, OF BROAD BROOK, CONNECTICUT.

DUMP-WAGON.

No. 880,733.

Specification of Letters Patent.

Patented March 3, 1908.

Application filed June 17, 1907. Serial No. 379,381.

To all whom it may concern:

Be it known that I, JOSEPH F. HAYES, citizen of the United States of America, residing at Broad Brook, in the county of Tolland and State of Connecticut, have invented certain new and useful Improvements in Dump-Wagons, of which the following is a specification.

My invention relates more especially to that class of dumping wagons or carts having side parts constituting a portion of the frame and upon which the body is mounted, and the object of my invention is to provide a device of this class which shall enable an extremely free and easy movement of the body to be obtained in the dumping operation, and also one in which the body is nicely balanced; and a further object of the invention is to provide a means that while serving as a support upon which the body is pivoted also acts as a strengthening means for the frame. A form of device in the use of which these objects may be attained is illustrated in the accompanying drawings in which

Figure 1 is a side view of a wagon embodying my invention. Fig. 2 is a detail perspective view on enlarged scale of a portion of the frame of the vehicle embodying my invention. Fig. 3 is a detail view in vertical cross-section through one of the side parts of the frame or reach, showing the method of mounting the body. Fig. 4 is a view in cross-section through the body support.

In the accompanying drawings the letter *a* denotes the rear wheels, *b* the front wheels, *c* the body, *d* the pole and *e* a platform upon which a seat *f* is located, all of these parts relating to a dumping wagon and being of usual form and construction, as plainly shown in Fig. 1 of the drawings.

The numeral 6 indicates the side parts of the reach or frame of the running gear which are secured at or near their ends in any desirable and convenient manner to the axle *g*. There are two of these side parts 6 located underneath the sills 7 at each side of the wagon body. The rear end of each of the side parts 6 is curved as at 8, this curve being on the arc of a circle the center of which is coincident with the center of the supporting rod 9. This supporting rod extends between the side parts 6 of the frame or reach and is secured as by means of bolt ends 10, one at each end of the rod. A shoulder 11 near each end of the rod opposes the thrust of the nuts upon the bolts 10, and this construction

firmly unites the side parts 6 of the frame or reach.

A plate 12 is set into the inner surface of each of the side parts 6 of the reach, the shoulder 11 on the rod 9 preferably abutting against this plate. A bracket 13 is pivotally mounted upon the rod or support 9, this bracket being secured at its upper end to the sill 7 of the wagon body, it of course being understood that there is a bracket secured to the sills at opposite sides of the wagon body. The lower end of this bracket is formed into a hub 14 with an opening therethrough of a size somewhat larger than the rod or support 9, the latter projecting through this hub. Roller bearings 15 are located between the inner surface of the hub and the outer surface of the rod or support, thus forming a means whereby the wagon body may be easily moved or rotated upon the support. A retaining plate 16 also located upon the support closes the chamber within which the roller bearings 15 are located and a sleeve 17 fitted upon the rod extends between the retaining plates 16 appurtenant to each of the brackets 13. This sleeve forms a means for retaining the parts in position and also acts as a spacer for the parts at opposite sides of the frame or reach.

The curved portions 8 form a guide about which the sills 7 of the wagon body move in the dumping operation, the main part of the weight of the wagon body in this dumping operation however being borne by the support 9. It will be noted that on account of the proximity of the brackets 13 to the side parts 6 of the reach that a supporting rod 9 of comparatively small dimensions may be employed and yet be sufficiently strong to support the weight required of it. The weight of the body of course when the latter is in a horizontal position is borne by the frame composed in part of the side parts 6.

What I claim as my invention and desire to secure by Letters Patent is:—

1. In combination with an axle and its supports, a frame including side parts secured to the axle, a wagon body including sills overlying the side parts, a support extending between the side parts and firmly secured to each to prevent lateral movement thereof, and brackets secured to the sills.
2. In combination with an axle and its supports, a frame including side parts secured to the axle, a wagon body including sills overlying the side parts, a support hav-

- ing a shoulder engaging each of said side parts and secured at the outer surface thereof, and brackets secured to the sills and pivotally engaged with said support.
5. 3. In combination with an axle and its supports, a frame including side parts secured thereto, a wagon body including sills overlying the side parts, a support extending between the side parts and secured at the 10 outer surface of each, a bracket secured to each sill and pivotally engaging said support, and a spacer located between said brackets.
4. In combination with an axle and its supports, a frame including side parts secured to the axle, a wagon body including sills overlying the side parts, a support extending between the side parts and firmly secured to each to prevent lateral movement thereof, brackets secured to each sill and 15 each having an opening forming a chamber, anti-friction bearings located in said chambers between the brackets and the supports, a plate on the support closing each of said openings, and a spacer extending between 20 said plates.
5. In combination with an axle and its supports, a frame including side parts secured to the axle, a wagon body including 25
- sills overlying the side parts, a plate secured to the inner face of each side part, a support having a shoulder engaging each of said plates and projecting through each side part and secured at the outer surface thereof, a bracket secured to each sill and having an opening for the reception of said support, anti-friction bearings located in said opening between the support and brackets, a plate closing said opening, and a spacer located on the support and between said plates.
6. In combination with an axle and its supports, a frame including side parts secured to the axle, a wagon body mounted upon the side parts and having sills, a support extending between the side parts, a bracket secured to each sill and having an opening for the reception of said support, anti-friction bearings located in said openings between the support and the brackets, and means for closing the openings in the brackets.

In testimony whereof I affix my signature in presence of two witnesses.

JOSEPH F. HAYES.
